(57) **CLAIM**

The ornamental design for a catalyst carrier for gas purification, as shown and described.

DESCRIPTION

FIG. 1 is a perspective view of a catalyst carrier for gas purification illustrating my new design;

FIG. 2 is a front view thereof;

FIG. 3 is a top view thereof, the bottom view thereof being a mirror image;

FIG. 4 is a right side view thereof, the left side view thereof being a mirror image;

FIG. 5 is an enlarged partial front view thereof;

FIG. 6 is a cross-sectional view taken through line 6-6 of FIG. 2; and,

FIG. 7 is a middle omitted cross-sectional view taken through line 7-7 of FIG. 5.

The broken lines in the drawings depict unclaimed subject matter only and form no part of the claimed design.

The catalyst carrier for gas purification is shown with a symbolic break in its length in FIG. 7. The appearance of any portion of the article between the break lines forms no part of the claimed design.
